UNITED STATES PATENT OFFICE.

CARL R. KLOK, OF CHICAGO, ILLINOIS, ASSIGNOR, BY MESNE ASSIGNMENTS, TO UNITED TABLE-BED COMPANY, A CORPORATION OF VIRGINIA.

TABLE-BED.

1,246,612.

Specification of Letters Patent. Patented Nov. 13, 1917.

Application filed January 16, 1914, Serial No. 812,532. Renewed September 17, 1917. Serial No. 191,896.

To all whom it may concern:

Be it known that I, CARL R. KLOK, a citizen of the United States of America, and resident of Chicago, Cook county, Illinois, 5 have invented a certain new and useful Improvement in Table-Beds, of which the following is a specification.

My invention relates to table beds of that kind in which the folding bed frame is 10 mounted to revolve or rotate about a horizontal axis, while in a folded condition, whereby the rectangular bundle formed by the folded bed frame is movable relative to the table body, when the same is to be folded 15 or unfolded.

The object of my invention, as herein shown and described, is to provide a novel construction and arrangement whereby the axis of rotation of the bed frame is movable 20 about another axis, as by rotatively mounting the bed frame on a swinging carrier frame, whereby the bed is movable about a plurality of axes, when in a folded condition, and is not fixed in the table body.

It is also an object to provide certain details and combinations tending to increase the general efficiency of a table bed of this particular character.

To the foregoing and other usual ends, my 30 invention consists in matters hereinafter set forth and claimed.

In the accompanying drawings—

Figure 1 is a longitudinal section of a table bed embodying the principles of my 35 invention, on line 1—1 in Fig. 2.

Fig. 2 is a section on line 2—2 in Fig. 1.

Fig. 3 is a view similar to Fig. 2, but showing the carrier frame swung into position to permit unfolding of the bed frame.

40 Fig. 4 is a similar view showing the bed unfolded.

Fig. 5 is an enlarged detail section on line 5—5 in Fig. 3.

Fig. 6 is an enlarged detail section on line 45 6—6 in Fig. 4.

As thus illustrated, my invention comprises a table body A, having legs a, disposed at the four corners thereof, and having fixed end walls a¹ and a fixed side wall 50 a², the top a³ and other side wall a⁴ being removable in any suitable or desired manner.

The folding bed B comprises a rectangular iron frame composed of sections b, b¹ and b² which are pivotally connected together by links b³ and b⁴, the latter being

shorter than the former. A carrier frame C is pivoted on the end walls of the table at c, and the section b is pivoted on said carrier frame at c¹, whereby the bed frame, when folded in the manner shown in Fig. 3, is adapted to rotate about a horizontal axis, while the said carrier frame is in a vertical position. When the bed frame is folded, the section b² is disposed between sections b and b¹, and space is also provided 60 for the mattress and bedding. A strap b⁵ can be provided for holding the bed frame in folded condition, and the carrier frame may be provided with pivoted locks or catches c² for engaging the bed frame, 70 whereby the latter is locked and held parallel with the carrier frame. In this condition, the carrier frame and bed frame can be swung upward and over, in the direction of the table body, until the carrier frame 75 rests on the stop D, which latter is fixed on the table body. In such position the swivel section b is upside down.

When the bed is extended as shown in Fig. 4 the frame is supported by pivoted legs E, 80 of any suitable character, connected to the links b³ and b⁴ at their upper ends by long links e and e¹, whereby these legs automatically fold and unfold when the bed frame is folded and unfolded also; and when the bed 85 frame is extended the links b³ are prevented from sagging by the stops F which engage the end of the section b, holding it in the position shown in Fig. 4; but these stops F are pivoted at f, if found desirable or necessary, so that they may be folded flat-wise against the inner surface of the end wall a¹, thus preventing interference with the folding and unfolding of the bed frame. To unfold the bed frame, the carrier frame C is 95 lifted upward from the stop D, and brought over and then downward to the position shown in Fig. 3, and then the strap b⁵ is detached and the bed frame unfolded. Thus the bed is brought to a large extent outside 100 of the table, and only projects a short distance within the table when in use. Any suitable means can be employed for making the table top a³ and a⁴ removable to permit said folding and unfolding of the bed.

With the foregoing construction, therefore, it will be seen that the invention involves one method of combining a table with a transversely folding bed frame, the sections of which are in three superimposed 105 110

layers when folded, in such a manner that the bed is of proper height when unfolded and whereby the table is also of the proper or standard height when the bed is folded. 5 Furthermore, notwithstanding the fact that the bed folds into three superimposed layers, the table is characterized by sufficient clearance below, so that it can be used comfortably and without inconvenience like an 10 ordinary table. Again, the bed when of standard length, and when entirely folded, in combination with the structure shown, results in a table of the ordinary or usual width employed for library or similar tables, 15 so that the table can be moved around and pushed through ordinary doorways in the usual manner. The invention, therefore, affords one way of solving some of the problems involved in so combining a folding 20 bed frame of this kind with a table so that the result will be a structure which is a satisfactory table and also a satisfactory bed, the standard requirements of neither one being sacrificed to the other. But, of 25 course, I do not limit myself to the exact construction shown and described.

What I claim as my invention is—

1. A table bed comprising a body having a movable top and side, a carrier frame 30 movably mounted on said body, means to support said frame, and a folding bed frame rotatively mounted on said carrier frame.

2. A table bed comprising a body having a movable top and side, a carrier frame 35 movably mounted on said body, and a folding bed frame rotatively mounted on said carrier frame, said carrier frame being pivoted to swing directly upward from its position in the table, to bring said bed 40 frame into position for unfolding.

3. A table bed comprising a body having a movable top and side, a carrier frame movably mounted on said body, and a folding bed frame rotatively mounted on said 45 carrier frame, said bed frame including pivotally connected sections, one of which sec-

tions is swiveled on the carrier frame, and said swiveled section being upside down when the bed is folded within the table.

4. A table bed comprising a body having 50 a movable top and side, a carrier frame movably mounted on said body, and a folding bed frame rotatively mounted on said carrier frame, said bed frame having provisions whereby a mattress may be folded 55 therewith.

5. A table bed comprising a body having a movable top and side, a carrier frame movably mounted on said body, and a folding bed frame rotatively mounted on said 60 carrier frame, and means for locking the frames together when the bed is folded.

6. A table bed comprising a body having a movable top and side, a carrier frame movably mounted on said body, and a folding bed frame rotatively mounted on said 65 carrier frame, and means for engaging the bed frame, when the bed is unfolded, carried on the body.

7. A table bed comprising a body having 70 a movable top and side, a carrier frame movably mounted on said body, and a folding bed frame rotatively mounted on said carrier frame, and means fixed on the body for supporting said frames within the table 75 and engaging the carrier frame when the bed is folded.

8. A table bed comprising a body having a movable top and side, a carrier frame movably mounted on said body, and a folding bed frame rotatively mounted between 80 its ends on said carrier frame, said bed frame including pivotally connected sections, links connecting the sections, providing space for a mattress, and folding legs 85 for the bed frame.

Signed by me at Chicago, Illinois, this 23rd day of December 1913.

CARL R. KLOK.
